SPEAKER ATTACHMENT FOR RADIOS

Anna Ptáček, New York, N. Y.

Application December 11, 1943, Serial No. 513,844

2 Claims. (Cl. 179—149)

This invention relates to new and useful improvements in a speaker attachment for a radio.

More particularly, the invention contemplates the association of a speaker attachment for a radio sender. It is proposed to use the sender in combination with a radio receiver. With this arrangement it is possible to receive as well as to send radio messages and other material.

More specifically, the invention proposes in a radio set, a cabinet having a compartment for a microphone for the radio set, and a novel arrangement of foldable supporting arm for said microphone, normally disposed within said compartment and adapted to be extended to various positions.

A novel arrangement is also proposed for holding the foldable arm with its microphone extended to a convenient position for broadcasting.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a combined radio receiver and radio sender provided with a speaker attachment in accordance with this invention.

Fig. 2 is a fragmentary enlarged sectional view taken on the line 2—2 of Fig. 1, but illustrated with the microphone extended.

Fig. 3 is a fragmentary enlarged vertical sectional view taken on the line 3—3 of Fig. 2.

Fig. 4 is a horizontal sectional view taken on the line 4—4 of Fig. 3.

Fig. 5 is a fragmentary plan view looking in the direction of the line 5—5 of Fig. 2.

The speaker attachment for a radio, in accordance with this invention, is used in combination with a radio set 10 having a cabinet 11 provided with a compartment 12. A door 13 is mounted on the cabinet for closing said compartment 12.

A foldable tubular arm 15 is mounted within the compartment 12 and supports a microphone 16 for the radio set. Means is provided for holding said foldable arm 15 in various extended positions. The foldable arm 15 includes a short tubular base section 18 and a plurality of alternating long sections 19 and short tubular sections 20. The outermost long section 19 supports the microphone 16. The adjacent end portions of said sections are connected together with universal joints. Each of these universal joints 55

includes a socket portion 21 on one of the sections engaged by a ball portion 22 on the adjacent one of said sections.

The means for holding the arm 15 in extended positions includes a cable 23 extended through the sections of said arm 15. The inner end of the cable 23 is attached to a pin 24 mounted across the outermost section 19. This cable 23 is guided through guide pieces 25 mounted within the ball portions 22 or said universal joints. The cable 23 extends out from the bottom of the compartment 12 and engages around a roller 26 turnably mounted on a bracket 27. The cable 23 continues and engages through a bayonet slot 28 formed upon a top panel 29 on the cabinet 11. This bayonet slot 28 has a near branch 28^a and a far branch 28^b. A ball 31 is mounted on the end of the cable 23.

Adjacent each of said universal joints of said foldable arm 15, there is an abutment collar 32. Each abutment collar 32 is threadedly mounted on a section of said foldable arm 15. It is provided with a flange 33 by which it may be conveniently turned. It is also provided with a socket portion 34 adapted to engage over and abut against a point or points of said adjacent joint.

When the ball 31 at the end of the cable 23 is in the bayonet branch 28^a, said cable 23 is loose. The foldable arm 15 may then be folded and dropped into the compartment 12, as indicated by the dot and dash lines. When it is desired to extend the microphone 16 it is merely necessary to lift the outer end of the foldable arm 15 outwards and hold the foldable arm 15 in any convenient position. The cable 23 is then pulled, and the ball 31 is moved over to the far end 28^b of the bayonet slot 28. This pulls the cable 23 tight.

It is advisable that the cable 23 be slightly stretchable so that its resilient contracting action when tight, forces the various sections composing the foldable arm 15 together, in relation to each other. This tightly engages the ball portions 22 and the socket portions 21 of the universal joints, locking them in position. If one, or more of said universal joints slips, and does not maintain a desired position, it is merely necessary to screw the abutment collar 32 downwards until the socket portion 34 engages and grips and holds said universal joint in a locked position.

A feature of the invention resides in the fact that the radio set may be used to receive radio in the usual way. When desired it may be used to transmit radio. In the latter case it is merely

necessary to extend the microphone into usable position.

It is to be understood that this radio device may be of various designs and may be operated either on the usual house current or by electric batteries.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a radio set having a compartment for a microphone mounted on one end of an arm having its other end mounted in said compartment and formed of separate tubular sections with ball and socket joints connecting the sections permitting it to be collapsed into said compartment, means for locking said ball and socket joints against collapsing when extended from said compartment, comprising a cord extended through said tubular sections, said cord having one of its ends attached to the outer sections of said arm and its other end extended from the inner section of said arm, and means on the latter end of said cord for holding it taut to maintain the arm against collapsing, comprising a ball secured on the end of said cord after the latter has been

5 passed through a bayonet slot, said slot having a branch spaced from said arm for holding the cord taut and a branch positioned closer to said arm to relax said cord when located therein freeing said arm to collapse.

2. In a radio set having a compartment for a microphone mounted on one end of an arm having its other end mounted in said compartment and formed of separate tubular sections with ball and socket joints connecting the sections permitting it to be collapsed into said compartment, means for locking said ball and socket joints against collapsing when extended from said compartment, comprising a cord extended through said tubular sections, said cord having one of its ends attached to the outer sections of said arm and its other end extended from the inner section of said arm, and means on the latter end of said cord for holding it taut to maintain the arm against collapsing, comprising a ball secured on the end of said cord after the latter has been 10 15 20 25 30 passed through a bayonet slot, said slot having a branch spaced from said arm for holding the cord taut and a branch positioned closer to said arm to relax said cord when located therein freeing said arm to collapse, said branches being connected and said ball being of a diameter greater than the width of said branches to be used for moving the end of said cord from one branch to the other.

ANNA PTÁČEK.
